UNITED STATES PATENT OFFICE

GÜNTHER LAUBMEYER, OF KASSEL-WILHELMSHÖHRE, GERMANY

METHOD OF AND APPARATUS FOR DETECTING THE PRESENCE OF PROFITABLE DEPOSITS IN THE EARTH

Application filed December 3, 1929, Serial No. 411,378, and in Germany August 1, 1929.

The object of my invention is a method of detecting profitable deposits in the earth and an apparatus for carrying out this method.

During the last ten or fifteen years methods 5 of practical geophysics are applied in a continually improving manner for detecting profitable deposits.

The method of my invention essentially differs from the geophysical methods hitherto known. While the familiar methods as the seismic, the geoelectric, the magnetic, and the gravimetric ones only allow to give an idea of the subterranean structure by the differences of physical constants of the obtrusive bodies, or by the differences of the different geological strata (geological conditions naturally being of great influence as regards the finding of the final result) my new method directly detects the deposits.

This new method is, therefore, much less dependent upon possibilities of obstruction which eventually may lead to entirely false results. The method according to my invention consists in collecting underground-air 20 by means of a special apparatus and in testing it quantitatively as to the existence of certain gaseous substances which are in direct relation with the deposits. The apparatus used for working the method is constructed 25 with the purpose of not giving any possibility of interchange with the open air to the underground-air which has been collected by certain parts of the apparatus. The apparatus is preferably constructed as a closure or lid 30 for borings, the lid having besides an outlet pipe at least one bell-shaped cylinder or the like surrounding the outlet pipe; the diameter of this cylinder is larger than that of the boring hole. A particularly preferred construction which has been found very practicable contains two cylinders arranged one 35 concentric to the other which are connected with an outlet pipe and which close the boring hole tightly.

In the drawings an apparatus according to the aforesaid invention is illustrated by way of example.

Fig. 1 is a diagrammatic view of the manner of working the apparatus and turning 40 the results into practice.

Fig. 2 shows a part of the apparatus in sectional view.

Fig. 3 is plan view of the apparatus.

Fig. 4 illustrates the apparatus ready for application.

Fig. 5 shows an apparatus in section inserted into the earth.

In Fig. 1 A indicates a stretch or layer of valuable deposits. The deposit may be assumed to be a coal containing a great percentage of gas. There will be boring holes made, for instance at the points 1 to 12 into which the apparatus for collecting underground-air duly to be described will be inserted in such manner that the underground-air collected by it and the gaseous substances slowly diffusing upwards which are contained in the underground-air and which slowly make their way through the covering strata cannot find an outlet into the open air. 50 The collecting devices—which may be termed “gasometers” on account of their bell-shaped cylinders serving for the collection of underground-air—are left at their places for about 24 to 48 hours after being inserted. The required time having expired small quantities of air are taken from these devices and are examined as to their contents of methan produced by the coal-deposit nearby. The proportional values obtained will then be registered according to a pattern like Fig. 1. A curve like curve C will for instance be the result. Above the deposits—eventually more or less shifted by tectonic conditions—a maximum of concentration of those gaseous substances which come into consideration with regard to the deposits will be found. From this concentration-curve or from several of them which eventually may have been caused by tests in different directions crossing each other, one may draw conclusions regarding the position, extension, and the approximate depth of the deposits in the earth. 65 70 75 80 85 90 95

It may be remarked that in testing the gaseous substances emanating from the deposits chiefly those come into question the molecular weight of which does not, at least not essentially, differ from that of the air.

The apparatus is equally appropriate for searching gas and oil deposits. As the 100

breadth and height of the measured maximum in the concentration curve allows certain conclusions regarding depth and extension of the deposits this procedure giving the direct 5 prove of the existence or non-existence of a desired deposit is superior to any other indirect geophysical methods.

The apparatus shown in Figs. 2-5 for collecting underground-air consists of two chief 10 parts. The one chief part may be called "earth-flange". It contains two hollow cylinders, 1 and 2, concentric to each other which are connected by a ring-like flange 3. The second chief part of the apparatus consists 15 of a lid 4 and a gas or outlet pipe 5, the latter being provided with a tap 6. Both the cylinders 1 and 2 may be made integral, for practical reasons, with ring-flange 3. These three parts may, however, be firmly connected with 20 each other. Lid 4 and gas pipe 5 are also preferably firmly connected together. In assembling the apparatus a tightening-plate 7 made, for instance, of india rubber is placed 25 between the earth-flange and lid 4. The two chief parts and the tightening plate are kept together by screws 8 and thumb-nuts 9.

If the apparatus is to be used for extracting underground-air a boring hole 10 of about 30 eight centimeters diameter and one to two meters depth is first of all bored with an earth 35 borer (Fig. 5). Then the earth-flange 1, 2, 3 is driven into the earth concentric to the boring hole i. e. so far that—as Fig. 5 shows—the upper rim of the earth-flange will be about 40 2 to 3 centimeters above the ground. Then the tightening plate 7 will be put on and the gas pipe is introduced into the boring hole whereupon the two chief parts of the apparatus are tightly screwed together by screws 45 8 and nuts 9. The parts must be so firmly united that the undergronnd-air enclosed in the boring hole and in space 11 cannot escape without having to overcome a great resistance. Space 11 is limited above by the lid, below 50 partly by the surface of the earth and partly by the boring hole, and at the sides by the walls of cylinder 2.

It is essential for the construction of the apparatus that the path to the outer air (and 55 vice versa) for the underground-air included in the boring hole 10 and in space 11 be as long as possible. This path of escape is denoted by dash and doited lines in Fig. 5. It runs first of all downwards along the inside wall- 60 ing of cylinder 2, then upwards along its outside through the space included between cylinders 2 and 1, then downwards along the inner walling of cylinder 1, and finally upwards along this walling to the outer air. 65 This path of escape is in the illustrated and described apparatus with the two cylinders 1 and 2 so large that an exchange between the included underground-air and the open air does not take place. When, therefore, at 70 opening tap 6 after about 24 or 48 hours a

small quantity of the underground-air is taken this quantity contains all the substances of importance for the examination.

It seems possible to construct the apparatus only with one hollow cylinder. The condition is only that this cylinder surrounds the outlet pipe bell-shape like and that its diameter be larger than that of the boring hole. In this case, however, the path of escape might prove too unsafe in practice, even if rather a long cylinder is used, so that probably an exchange between the underground-air collected in the apparatus and the outer air might occur. Therefore the described form with two hollow cylinders concentrically arranged is preferable because of the longer path of escape. The apparatus might also be provided with more than two hollow cylinders lying concentrically to each other, as hereby the path of escape will be made larger still and the possibility of an exchange between the collected air and the open air will be less.

I claim:

1. Method of detecting valuable deposits in the earth by means of a relatively shallow earth bore which consists in collecting underground-air in the shallow bore, and quantitatively examining the collected air with respect to the presence of gaseous substances directly related to said deposit, for the purpose of determining proximity to the valuable deposits.

2. Method of detecting valuable deposits in the earth by means of a relatively shallow earth bore which consists in collecting a quantity of underground-air in the shallow bore, confining said quantity in a space closed against the outer air, drawing off a part of said confined quantity, and examining said drawn off part with respect to the presence of gaseous substances directly related to said deposit.

3. Apparatus for detecting valuable deposits in the earth comprising a relatively shallow earth bore for collecting a quantity of underground-air, means including a closure plate of extent greater than the size of the bore for confining said quantity out of contact with the outer air, and means for drawing off part of said confined quantity.

4. Apparatus for detecting valuable deposits in the earth comprising a closure for a boring hole, two bell-shaped cylinders concentric to each other adapted to be inserted into the earth concentrically to the boring hole, closing means connected to said cylinders for closing a space surrounded by said cylinders against the atmosphere, and means connected to said closing means for drawing off underground-air from said space.

5. Apparatus for detecting valuable deposits in the earth comprising a closure for a boring hole, two bell-shaped cylinders concentric to each other adapted to be inserted into the earth concentrically to the boring

hole, a tightening plate secured to the upper rim of said cylinders for closing a space surrounded by said cylinders, a pipe connected to said tightening plate, one end of said pipe being open to said space, the other end of said pipe being open to the atmosphere, and a tap on said pipe for drawing off underground-air confined in said space.

6. A method for locating valuable underground deposits in the earth by collecting a quantity of underground air at different points in a systematic manner throughout a region and quantitatively analyzing portions of the underground air for the presence of constituents that are characteristic of the presence of deposits in order to determine proximity to and extent of the valuable deposits.

7. Apparatus for detecting valuable deposits in the earth, comprising an open ended gas collecting member adapted to be inserted in the ground around a shallow earth bore, a lid or closure for one end of the open ended member, the said lid extending downwardly to beyond the limits of the bore, and means through which a sample of the collected gas may be removed.

8. In an apparatus for detecting valuable deposits in the earth, comprising a plurality of open ended cylinders adapted to be inserted into the ground surrounding a shallow earth bore for the purpose of entraining a quantity of underground gas, a common closure plate extending over one end of both cylinders and hermetically sealing that end, and means for withdrawing a portion of the entrained gas, the said means passing through the common closure plate.

In testimony whereof I affix my signature.
